10 Claims. (Cl. 178—70)

1

The present invention relates to telegraph repeaters and regenerating and distortion eliminating devices for telegraph modulated signals sent out in the arrhythmic or start-stop code.

One of the objects of the present invention is to provide a device of the general character above referred to comprising means for sending current impulses, said means being controlled by an oscillator, thereby insuring greater stability than has heretofore been possible.

Another object of the present invention is to provide a device of the general character above described with novel means for insuring the marking or determination of the operating times with precision.

These and such other aims and objects of the present invention as may hereinafter appear will be readily understood from the following description, taken in connection with the accompanying drawing, of one illustrative embodiment of the present invention.

It is known that when using disturbed telegraph lines or telegraph lines of great length, the telegraph keying modulation of the signal characters which reaches the receiving end of the line often suffers considerable distortion, particularly when the line is made of several sections, the transmitting relay for each section being connected to the receiving relay terminating a preceding section. It is, therefore, necessary to provide devices to correct such distortions and reshape the distorted pulses constituting the elements of the signal. Various expedients have been used for this purpose.

It is here proposed to use for each group of the signal keying modulation received, a group of short current impulses or signal elements precisely separated from each other by a unitary interval or time element of said modulations. This group of short current impulses representing a character may consist, for example, of seven such short impulses, if the code used is a five element code plus a starting and stop signal.

Suitable means are provided in the regenerating system of the present invention whereby the first of said current impulses occurs one-half of a unitary interval after the arrival of the starting signal element. As a result, the impulses that follow occur at moments corresponding exactly to the mid-point of the theoretical intervals relative to each element of the code used. A device is provided which receives the signal modulation to be re-shaped and re-transmitted, and gives passage to short current impulses directed in the same sense or direction, so that they flow through

2

a winding of a polarized relay in one or the other direction, according to the polarity of the modulation signal elements received at the moment that said impulses arrive. The short current impulses thus determine the instants when the armatures of the polarized relay are displaced or rocked, the direction in which said armatures are rocked being determined by the polarity of the signal element received. This polarized relay thus restores the signal keying modulation which is received, free of distortion and with a displacement of time or phase equal to one-half of the unitary interval.

In the drawing:

15. Fig. 1 is a block diagram of the signal regenerator system;

Fig. 2 is a diagram showing the time operating sequence of the several signal elements as they occur in the regenerator;

20. Fig. 3 is a circuit of a system incorporating the improved signal regenerator for a telegraph line.

Generally speaking, the present improved regenerator includes an oscillator whose frequency is accurately adjusted so that the length or period of a cycle of the output has a value equal to the theoretical duration of the unitary time element or interval of the element of the signal being transmitted. This oscillator is normally blocked but is instantaneously unblocked with a predetermined initial phase upon the arrival of each starting element of the received signal group, and afterwards blocked again, responsive to the operation of an impulse counter at the theoretical instant which corresponds to the mid-point of the final stopping signal element of the signal group, assuming said stopping element to have a duration equal to that of the code elements of the character itself.

45. Oscillations thus generated cause a train (for each signal group) of a sequence of short current impulses (say seven in number) which appear at a particular point of each cycle of the oscillation and are consequently accurately spaced from one another by a unitary interval. The first of such oscillations has its positive peak, due to a device adapted to adjust the oscillation phase, half a unitary interval after the arrival of the starting signal element. It follows that the subsequent impulses appear at instants which exactly correspond with the mid-point of the theoretical intervals of each code signal element.

50. A current reversing device is provided for receiving the incoming keying modulated signal to be regenerated or reshaped and for allowing

passage of short current impulses which all have the same direction, in such manner that they flow through the winding of a relay in either direction, depending upon the polarity of the received signal modulation element as they arrive.

The short current impulses consequently determine the displacement or rocking times or instants of the armature of the relay, the direction of the rocking action being dependent upon the received polarity of the signal element. Such polarized relay restores or re-shapes without any distortion the elements of the received signal train and with a time lag equal to half a unitary interval of the signal element. As a result of this, it corrects both the irregular distortion and the rate of keying modulation. The maximum distortion of the received modulation signal that can be possibly regenerated or reshaped, is limited only by the duration of the short current impulses or elements. The latter should be long enough to actuate the polarized relay.

In the system of Fig. 1, the modulation of the keyed signal received on the incoming line L_1 operates an input relay RE , the duty of which is to block or unblock an oscillator O . Oscillations delivered by this oscillator flow to a phase shifter D and control a short current pulse shaper or emitter I . Such pulses or impulses, as well as the modulation of the keyed signal received by the incoming line L_1 , are applied to current reversing means which may illustratively comprise a set of rectifying cells RS associated with a polarized output relay R . The regenerated modulation constituting the keyed signal is delivered at the output from reverser RS on the outgoing line L_2 . An impulse counter CI counts the impulses delivered by the emitter I and, as the seventh impulse occurs, releases the input relay RE , thereby blocking the oscillator O , and resumes its unoperated position.

In Fig. 2 are represented the operating instants or times of the several elements of the system.

At (a) in Fig. 2, is shown the perfect signal elements of a typical seven element train or group, representing a letter, as emitted by a transmitter at the remote end of an incoming line L_1 .

At (g) and (h) in Fig. 2, are shown extreme possible types of distorted signals arriving at the repeating regenerating station and applied to input relay RE and also direct to the winding of polarized output relay R , which distorted signals can be reconstituted into the originally transmitted perfect signal of Fig. 2(a) by the regenerator here described, as can likewise received signals whose elements are less seriously distorted.

Fig. 2 shows at (b) the movements of the armature of input relay RE , which closes, after a brief operating interval, after the arrival of negative initial starting impulse d , and remains closed until there have been counted, as by condenser storage, six following impulses, the last being the stop impulse (a) of positive polarity which de-energizes input relay RE . During the time that input relay RE is thus closed, as shown at Fig. 2(b), it unblocks oscillator O of the keying element frequency, which over the same period of time delivers oscillations as shown at (c) in Fig. 2. The phase of these oscillations is shifted so that, as shown at (d) in Fig. 2, the peaks are the mid-point of the interval of each of the signal elements.

Short pulses, as shown at (e) in Fig. 2, are formed by a pulser on the positive peaks of the

phase-shifted oscillations shown at (d) in Fig. 2, and are applied to time a pole-changing output relay in accordance with the polarity of incoming signal elements, producing outgoing signal elements, as shown at (f) in Fig. 2, which are the same as the perfect signal elements shown at (a) in Fig. 2, but shifted by one-half of the length of the signal element.

In Fig. 2, is shown at (a) by way of example, any perfect modulation signal as received on the incoming line L_1 and corresponding to a character. T is the duration of the unitary time interval of the signal code, the changes in the current direction occurring at the instants designated by $T, 2T, 3T, 4T, 5T$. The initial and final signal elements d and a are, respectively, the starting and stopping elements for the particular signal group, while the signal elements $1, 2, 3, 4, 5$, are the code elements representing a letter or figure. Fig. 2 also shows the movements of the armature of the input relay RE . This relay being in unoperated condition at the instant taken as zero time, its armature will be rocked on arrival of start element d , so that the oscillator O is unblocked a very short time O_1 (Fig. 2—d) following the arrival of the starting initial signal element d . Oscillations as applied by the oscillator O are represented at (c) in Fig. 2. After passing through the phase shifter D , they appear as shown in Fig. 2 at (d), each minimum corresponding to the instants $T, 2T, 3T$, and so forth, while each maximum corresponds to the mid-point of a modulation or keying element.

The pulse sender I delivers a short current pulse at each peak or maximum of the oscillations in the output of the phase shifter as shown at (e) in Fig. 2. The positions assumed by the armature i_2 of the double current polarized output relay R are illustrated at (f) in Fig. 2. Normally this armature is pulled from its left contact r_3 to its right contact t_3 when the first short current pulse reaches relay R , the direction in which said pulse flows through the exciting winding of the relay having been predetermined by the polarity of the modulation signal keying element. (Fig. 2—g.) As the second short impulse of the group of seven constituting the letter, reaches output relay R , it flows through the winding of polarized relay R in the reverse direction, since the polarity of the modulation keying signal element i is the opposite to that of initial starting signal element (d) and rocks the armature of relay R into contact with its left contact r_3 . The same phenomena occur for the other impulses of the group of seven shown in Fig. 2—g, constituting the letter. The fifth impulse for the character shown in Fig. 2—g has no effect on the output relay R because of its tendency to rock its armature into contact with the left contact r_3 against which it has been previously brought by the preceding impulse.

The seventh impulse counted by the impulse counter CI returns the input relay RE to rest position and blocks the oscillator O . The input relay RE operates very fast in returning to its rest condition.

As will be seen, keying signal elements of a received signal, although considerably distorted as those shown at (g) and (h) in Fig. 2, will still be correctly regenerated or reshaped since the polarity of the elements of the output during intervals of the pulse with O_2 duration (Fig. 2—e) which correspond to the several pulses, are similar to those of the corresponding elements of the

perfect modulation of the transmitted signal, as shown at (a) in Fig. 2.

Fig. 3 shows an illustrative possible application of a device embodying the present invention. As shown in this embodiment, the double winding input relay RE has two differential windings 1, 2, of which 2 is the weaker, the winding 1 being connected on the one hand to the incoming line L₁ and on the other hand to a current source +B.

The winding 2 of input relay RE is in the circuit of the pulse counter CI, and input relay RE is provided with a pair of armatures *i*₁ and *i*₂ in operative relation with the windings 1, 2, of input relay RE, said armatures vibrating through the gaps between contacts *r*₁, *t*₁, and *r*₂, *t*₂, respectively.

In unoperated position, the armature *i*₁ rests on contact *r*₁ while the armature *i*₂ rests on contact *r*₂. Should a signal element of positive polarity be received on the incoming line L₁, no current will flow through the winding 1 of input relay RE, this polarity being nullified by the positive current source +B. The oscillator O of the capacity-resistance type is then blocked, the condensers C₁, C₂, C₃, of its grid circuit being charged through contact *r*₁ with a predetermined positive voltage by a potentiometer P₁, so that their charge shall equal that corresponding to the peak of the oscillating plate voltage of the oscillator tube O when oscillating normally.

When relay armature *i*₁ is in rest position engaging contact *r*₁, there is no coupling between the plate circuit and the grid circuit of the oscillator tube O, so that this tube cannot oscillate and is blocked. When armature *i*₁ is in operated position engaging contact *t*₁, there is coupling between the plate circuit and the grid circuit of the oscillator tube, through condensers C₁, C₂, C₃, and the tube is unblocked and oscillates.

The impulse counter CI is constituted by a circuit including a capacitance 3 and a cathode resistance 4 associated with a gas discharge tube. When the armature *i*₂ of the input relay RE is on rest contact *r*₂, the grid 15 of the discharge tube has cathode potential, whereby this discharge tube becomes conductive and closes a circuit across the capacitance 3 between the positive terminal of battery HT, and the grounded negative terminal of battery HT. The current through this circuit flows through the differential winding 2 of the input relay RE and holds its armatures in contact with the contacts *r*₁ and *r*₂, under which circumstances they are in unoperated position. Thus, when the first charging impulse is applied to condenser 3, oscillator O remains blocked.

Upon the arrival of the starting element *d* of a signal train, a negative polarity exists on the line L₁, current flows from +B, and the principal winding 1 of the input relay RE is energized. The action of this winding 1, is stronger than that of the differential winding 2 of input relay RE, whereby the input relay RE rocks its armatures *i*₁ and *i*₂ into contact with actuated contacts *t*₁ and *t*₂, respectively. Owing to the contact made at *t*₁ the oscillator O is unblocked and the oscillation starts instantaneously owing to the charge which was delivered through contact *t*₁ to the capacitances C₁, C₂, C₃, of the grid circuit during the unoperated period, which charge corresponds to the voltage which is the peak plate voltage of oscillator tube O during normal operation. The initial phase of the oscillation corresponds to the peak of the plate voltage. (Fig. 2—c.) The grid

of the discharge tube of the impulse counter CI is connected at operated contact *t*₂ to a potential determined by a potentiometer P₂, whereby it is negatively polarized with respect to the cathode of said tube as determined by the cathode resistance 4. The gas tube of the impulse counter then ceases to be conductive, and the capacitance 3 is slowly charged from a current source +HT.

The oscillation delivered from oscillator O flows through the phase shifter D constituted by the capacitance 5 and the resistances 6 and 7; it trips the pulse sender I constituted by a triode-pentode connected as is known in the art to form a blocking relaxation oscillator by a double coupling between the pentode grid and the triode plate on the one hand, and to a cathode resistance 8 on the other hand. Pulses collected in the pentode plate circuit pass through transformers 9, 10. Each impulse as it passes through the transformer 10, transiently renders the grid of the gas discharge tube of impulse counter CI more positive, thereby approximating the value of its potential to that of the cathode. The time constant of the circuit including the capacitance 3 and resistance 4 is so calculated that the seventh impulse renders the gas tube of CI conducting. At this moment, the discharge current from the capacitance 3 passes through the winding 2 of the input relay RE and returns the armature of RE to unoperated position, closing contacts *r*₁ and *r*₂, thereby blocking oscillator O.

As they flow through the transformer 9 the short current impulses reach the set of rectifying cells 11, 12, 13, 14, constituting current reverser RS associated with the polarized output relay R, the armature *i*₃ of which comprises a permanent magnet and is connected to the outgoing line L₂, and can be rocked into contact with either one of the relay contacts *t*₃ and *r*₃, which are respectively connected to the telegraph line batteries +B and -B. When current flows through the two windings in series of relay R in one direction, the armature *i*₃ is rocked into engagement with relay contact *r*₃ if it is not already in engagement therewith. When current flows through the two windings in series of relay R in the opposite direction, the armature *i*₃ is rocked into engagement with right contact *t*₃ if it is not already in engagement therewith. The armature *i*₃ is usually in engagement with either *r*₃ or *t*₃, depending on the direction of the last pulse of current through the windings of relay R. The set of rectifying cells RS is of known construction and arrangement and comprises the four rectifying cells, 11, 12, 13, 14. When a positive polarity is applied to the incoming line L₁, currents flow through the transverse rectifier cells 12 and 13 and render them conductive. These currents have no action whatever on the output relay R, the current through one of the two windings 1 and 2 of the latter flowing in the opposite direction to that of the current flowing through the other. If, during the moment when cells 12 and 13 are thus rendered conductive, a pulse from emitter I flows through the transformer 9, it finds a conductive path through the conductive rectifying cells 12 and 13 and the two windings 1, 2, of the output relay R which are connected in series, whereupon this relay rocks its armature *i*₃ into contact with the left contact *r*₃ and a positive polarity is imparted to the outgoing line L₂.

Conversely, when a negative polarity is applied to the incoming line L₁, the rectifier cells 11, 14, are rendered conductive so that if, during this moment, a pulse from emitter I passes through

the transformer 9, it will flow through the rectifier cells 11, 14, and through the output relay R, but in the reverse direction. The output relay R then rocks its armature t_3 into contact with right contact t_3 and a negative polarity is imparted to the outgoing line L_2 . As will be seen, distorted impulses arriving through the incoming line L_1 cannot alone control the output relay R, the latter responding only to correct impulses furnished by the unit O, I, 9, which is determined by the oscillator. Signals sent through the outgoing line L_2 are consequently of correct shape.

I am aware that the present invention may be embodied in other specific forms without departing from the spirit or essential attributes thereof, and I, therefore, desire that the present embodiment of the invention be considered in all respects as illustrative and not restrictive, reference being had to the appended claims rather than to the foregoing description to indicate the scope of the invention.

What is claimed is:

1. A regenerating and distortion-eliminating device for telegraphic modulated signals emitted in the start-stop code, comprising on a telegraphic line an oscillator having a period equal to the theoretical duration of the unitary interval of the modulations requiring regeneration, an input relay located before said oscillator for blocking and unblocking the oscillator, a phase shifter fed by the oscillator, a short current impulse emitter tripped by said phase shifter, a current reversing device and polarized relay unit fed by said emitter and forming the output terminal of the regenerating and distortion eliminating device, and means shunted across the input relay and emitter for counting the impulses generated by said emitter and for actuating the input relay to block the oscillator while itself resuming its inoperative condition at the appearance of the seventh impulse of a sequence.

2. A regenerating and distortion-eliminating device for telegraphic modulated signals emitted in the start-stop code, comprising on a telegraphic line an oscillator having a period equal to the theoretical duration of the unitary interval of the modulations requiring regeneration, an input relay connected in the input of said oscillator for blocking and unblocking the oscillator, a phase shifter fed by the oscillator, a short current impulse emitter tripped by said phase shifter so as to center each impulse on the theoretical mid-points of the several code elements, a current reversing device and polarized relay unit fed by said emitter and forming the output terminal of the regenerating and distortion eliminating device, and means shunted across the input relay and emitter for counting the impulses generated by said emitter and for operating the input relay to block the oscillator while itself resuming its inoperative condition at the appearance of the seventh impulse of a sequence.

3. A regenerating and distortion-eliminating device for telegraphic modulated signals emitted in the start-stop code, comprising on a telegraphic line an oscillator having a period equal to the theoretical duration of the unitary interval of the modulations requiring regeneration, an input relay located before said oscillator for blocking and unblocking the oscillator, a phase shifter fed by the oscillator, a short current impulse emitter tripped by said phase shifter, a current reversing device and polarized relay unit fed by said emitter and forming the output terminal of

the regenerating and distance eliminating device, said reversing device comprising a rectifier bridge and determining the direction of flow of said impulses through said relay responsive to the polarities of each code element as received when the impulse appears, and means shunted across the input relay and emitter for counting the impulses generated by said emitter and for operating the input relay to block the oscillator while itself resuming its inoperative condition at the appearance of the seventh impulse of a sequence.

4. A regenerating and distortion-eliminating device for telegraphic modulated signals emitted in the start-stop code, comprising on a telegraphic line having an input terminal and an output terminal, an oscillator having a period equal to the theoretical duration of the unitary interval of the modulations requiring regeneration, an input polarized relay connected in the input of said oscillator for blocking and unblocking the oscillator, said relay including a pair of differential windings and armatures, one of the windings interconnecting the line input terminal and a current source, a phase shifter fed by the oscillator, a short current impulse emitter tripped by said phase shifter, a current reversing device and polarized relay unit fed by said emitter and forming the output terminal of the regenerating and distortion eliminating device, and an impulse counter including the other input relay winding for counting the impulses generated by said emitter and for actuating the input relay to block the oscillator while itself resuming its inoperative condition at the appearance of the seventh impulse of a sequence.

5. A regenerating and distortion-eliminating device for telegraphic modulated signals emitted in the start-stop code, comprising on a telegraphic line an oscillator of the capacitance-resistance type having a period equal to the theoretical duration of the unitary interval of the modulations requiring to be regenerated, an input relay connected in the input of said oscillator for blocking and releasing the oscillator, a phase shifter fed by the oscillator, a short current impulse emitter tripped by said phase shifter, a current reversing device and polarized relay unit fed by said emitter and forming the output terminal of the regenerating and distortion eliminating device, and an impulse counter bridging the input relay and emitter and comprising a condenser connected for storing pulses emitted by said pulse emitter for counting the impulses generated by said emitter and being connected for actuating the input relay said input relay being connected when actuated to block the oscillator.

6. A regenerating and distortion-eliminating device for telegraphic modulated signals emitted in the start-stop code, comprising on a telegraphic line, an oscillator of the capacitance-resistance and tube type including grid circuit condensers positively charged by potentiometer means, said oscillator having a period equal to the theoretical duration of the unitary interval of the modulations requiring regeneration, an input relay connected in the input of said oscillator for blocking and unblocking the oscillator, a phase shifter fed by the oscillator, a short current impulse emitter tripped by said phase shifter, a current reversing device and polarized relay unit fed by said emitter and forming the output terminal of the regenerating and distortion eliminating device, and an impulse counter bridging the input relay and emitter and comprising a

Condenser connected for storing pulses emitted by said impulse emitter for counting the impulses generated by said emitter and being connected for actuating the input relay, said input relay being connected when actuated to block the oscillator.

7. A regenerating and distortion-eliminating device for telegraphic modulated signals emitted in the start-stop code, comprising on a telegraphic line an oscillator having a period equal to the theoretical duration of the unitary interval of the modulations requiring regeneration, an input relay located before said oscillator for blocking and unblocking the oscillator, a phase shifter fed by the oscillator, a short current impulse emitter tripped by said phase shifter, a current reversing device and polarized relay unit fed by said emitter and forming the output terminal of the regenerating and torsion eliminating device, and an impulse counter bridging the input relay and emitter and comprising a condenser connected for storing pulses emitted by said impulse emitter for counting the impulses generated by said emitter and being connected for urging the input relay, said input relay being connected when actuated to block the oscillator, said counter including a capacitance and resistance unit associated with a discharge tube.

8. In a telegraph repeater regenerating system transmitting signal trains of signal elements of both polarities of uniform duration determined by a definite keying frequency including initial starting and final stop elements, an input relay having a principal winding and an opposing bias winding, an output polarized relay having two windings connected in series and having two controlled contacts, connected respectively for applying voltages of opposite polarity to its armature, a line input terminal connected to the common terminal of said windings of said output relay and also connected to said principal winding of said input relay, a blocking oscillator tube of said keying frequency and having its blocking circuit connected to a controlled contact of said input relay for becoming unblocked upon receipt of a start pulse by said input relay, a phase shifter connected to the output of said oscillator tube, a narrow pulse former connected to the output of said phase shifter and adapted to form a narrow pulse on the positive peaks of the output of said phase shifter, a rectifier bridge having two terminals connected to the output

of said pulse former and having its other two terminals connected to the outer terminals of the windings of said output relay, said rectifier bridge having only one of its pairs of arms conductive at a given time as determined by the polarity of the signal element applied at a given instant to said line input terminal, whereby the direction of application of pulses from said pulse former to the two windings in series of said output relay is determined by the polarity of the instantaneous signal element applied to the input terminal, and regenerated undistorted signals are delivered to the armature of said output relay.

15 9. A system according to claim 8, and an impulse counter unit comprising a gas triode and a condenser, said condenser being connected in the output circuit of said gas triode through said bias winding of said input relay, controlled contacts of said input relay connected for connecting the grid of said gas triode to its cathode when said oscillator is blocked and for connecting said grid of said gas triode to the output of said pulse former when said oscillator is unblocked, said output circuit of said gas triode including said condenser being adapted upon the receipt from said impulse former of the number of signal elements constituting a complete signal train including the final stop element, to cause said condenser to discharge and ionize said gas tube and actuate said input relay to stop said oscillator.

30 10. A system according to claim 8, the blocking circuit of said blocking oscillator comprising reactive elements adapted to initially apply to the plate of said blocking oscillator tube at the instant of unblocking a positive voltage which is the peak voltage of said blocking oscillator tube during normal operation, whereby upon unblocking the said oscillator tube starts its initial oscillation at its normal positive peak.
